UNITED STATES PATENT OFFICE.

ALBIN HELLFRITZSCH, OF MILWAUKEE, WISCONSIN.

INFANT'S COMBINATION-CARRIER.

1,139,762.

Specification of Letters Patent.

Patented May 18, 1915.

Application filed June 15, 1914. Serial No. 845,068.

To all whom it may concern:

Be it known that I, ALBIN HELLFRITZSCH, a subject of the Emperor of Germany, residing at Milwaukee, county of Milwaukee, 5 and State of Wisconsin, have invented new and useful Improvements in Infants' Combination-Carriers, of which the following is a specification.

My invention relates to improvements in 10 infants' combination carriers.

The object of my invention is to provide an infant's carrier, which is capable of being separated into individual units, readjusted and re-combined, or the units separately 15 used, for the performance of a variety of functions, whereby the device, (or separable units thereof), may be used as an ordinary chair, as a high chair, a swing, a baby walker, a table, as a combined table and 20 chair, or as an indoor push cart.

In the drawings—Figure 1 is a side elevation of a device embodying my invention as it appears when used as a chair, suitable hanger connections being illustrated in connection therewith, which are adapted to be employed when the device is adapted to be used as a swing. Fig. 2 is a side elevation of the same as it appears when reorganized and used as a combined chair and table, or 25 indoor push cart. Fig. 3 is a plan view of the chair unit, together with a fragment of the baby walker. Fig. 4 is a detail view from the underside, of the top ring of the baby walker and the table unit assembled 30 for use, with the fastenings in connecting position, and the standards broken away. Fig. 5 is a detail view of the suspensory or swing unit.

Like parts are identified by the same reference characters throughout the several views.

My device is composed primarily of four units—a baby walker unit, a table unit, a chair unit, and a suspensory or swing unit. 45 The baby walker unit comprises a pair of rings 1 and 2 connected with each other by a series of standards 3. The lower ring 1 is larger in diameter than the upper ring 2 and is provided with a set of casters 5. This 50 unit may be employed as an ordinary baby

walker, the upper ring 2 being of sufficient size to allow the body of any ordinary infant to pass through it, the ring supporting the infant's body with its feet resting upon the floor as is common with so called baby 55 walkers.

The standards 3 are provided with hooks 7, adapted to support a table top member 8. Said top is preferably circular in form and is adapted to be adjusted between the standards 3, as shown in Fig. 1, with its margins engaged by said hooks 7. This table top 8 is preferably provided with raised side margins 9 to retain articles placed upon the table. The under surface of the table top 60 member is provided with a depending circular member 11, which is adapted to enter the ring 2, when said top member 8 is unhooked from the standards 3 and superposed upon the ring 2 with member 11 registering with 65 the opening in said ring. The lower surface of the member 11 will then be flush with the bottom of the ring 2. Locking bolts 14, supported in suitable bearing clips 15 on the under surface of the bearing member 11, may then be shifted, as indicated in 70 Fig. 4, with the bolts projecting into engagement in socketed clips 17 secured to the under surface of the ring 2, thereby connecting the table top with the top ring 2 of 75 the baby walker, so that it cannot be accidentally dislodged.

The chair unit is adapted to be substituted for the table top member or unit upon the baby walker ring 2. The chair unit 85 comprises a seat 20 provided with legs 21 connected with a base ring 22, having casters 24 secured to the base ring 22 by downwardly projecting foot pieces 25. The chair back and arms are formed of an ordinary 90 bow shaped bar 27, connected with the seat by supporting rungs 28.

29 is a shelf guard of ordinary type, having one end pivoted to the bow 27 at 30 and the other detachably connected with the 95 opposing extremity of the bow 27 at 31.

The chair seat 20 is provided with a set of connecting members, such as eye screws 33, with which snap hooks 35 are adapted to be detachably engaged. The snap hooks 100

are connected with hangers 36, which may be composed of ropes, or any other suitable suspensory devices. These are preferably connected with a ring 37, whereby the device 5 may be suspended from an over-head support.

The base 22 of the chair is provided with a circular channel 38, which is adapted to receive the ring 2 of the baby walker. The 10 channel is of sufficient depth so that the under surface of the ring 2 will be flush with the under surface of the base 22, when the ring is in said groove 38. In this position the chair and baby walker may be secured 15 together by locking bolts 39 carried by the chair base. These locking bolts and their supports are similar to those carried by the table member 11 and they are adapted to engage the clips 17 on the under surface of the 20 ring 2 in the same manner. When the chair is thus superposed and secured to the baby walker, the latter serves as a stand and the combined units will constitute a high chair, as illustrated in Fig. 1. When the chair 25 unit is removed from this superposed position on the baby walker, it is adapted to be readjusted at the side of the latter as illustrated in Fig. 2, with the base 22 of the chair over-lapping the base ring 1 of the baby 30 walker. The foot members 25 are of sufficient height to allow the chair casters 24 to rest upon the floor and support the base 22 out of contact with the base ring 1. The 35 hooks 7 on two of the standards 3, may then engage the front eye screws 33 on the chair seat to lock the chair and baby walker together. The table unit will then be superposed on the baby walker, as also shown in Fig. 2, whereupon the entire apparatus, 40 with the exception of the swing hangers, may be moved from place to place as one unit, and an infant in the chair will be supported in a position to conveniently reach articles placed upon the table 8.

45 I claim—

1. An infant's combination carrier, including a baby walker unit, and a table top unit adjustable to either a superposed position of the baby walker unit or to a suspended position within the baby walker unit, and means for securing said table top unit in either position, substantially as described.

2. An infant's combination carrier, including a baby walker unit, a table top unit 55 adjustable to either a superposed position of the baby walker unit or to a suspended position within the baby walker unit, means for securing said table top unit in either position, and a chair unit interchangeable 60 with the table top unit in said superposed position, substantially as described.

3. An infant's combination carrier, including a baby walker unit, a table top unit adjustable to either a superposed position

of the baby walker unit or to a suspended 65 position within the baby walker unit, means for securing said table top unit in either position, and a chair unit interchangeable with the table top unit in said superposed position, said chair unit and said baby walker 70 unit each having a base provided with casters, the casters upon the chair unit being spaced from the base sufficiently to support the base from a floor at a higher level than the base of the baby walker unit, and the baby walker 75 unit base being apertured to permit one or more of the casters on the chair base to pass through it, when said bases are adjusted in interacting relation, together with means for connecting the chair unit and baby walker 80 unit above the bases when in such relation, substantially as described.

4. The combination of a baby walker unit provided with a caster supported base ring and also having a top ring, a chair unit 85 provided with a base having an annular channel therein to receive the top ring of the baby walker unit, and casters connected with said chair unit base and adapted to support the latter at a sufficient height to 90 allow it to overlap the base ring of the baby walker unit when the casters on both units are supported directly from the floor, whereby said units may interlap to form a combined chair and table, substantially as de- 95 scribed.

5. The combination of a baby walker unit provided with a caster supported base ring, a chair unit provided with a caster supported base adapted to lap over one side of 100 the baby walker base, and means for connecting the chair unit and baby walker unit above their bases, together with a table top unit normally connected with the baby walker unit intermediate of its top and bot- 105 tom, and adapted to be adjusted to a superposed position upon the baby walker unit to constitute a table, substantially as de- scribed.

6. The combination of a baby walker unit 110 provided with a caster supported base ring, a chair unit provided with a caster supported base adapted to lap over one side of the baby walker base, and means for connecting the chair unit and baby walker unit 115 above their bases, together with a table top unit normally connected with the baby walker unit intermediate of its top and bot- tom, and adapted to be adjusted to a superposed position upon the baby walker unit 120 to constitute a table, said chair unit being interchangeable with the table top unit in the superposed position upon the baby walker, and said table top unit and chair unit being each provided with means for 125 locking it in such superposed position.

7. The combination with a chair unit pro- 99 vided with a base having an annular channel

therein, and a supporting member provided with a ring adapted to engage in said channel, locking devices adapted to detachably connect said base and ring against accidental displacement, said chair unit and the supporting member being each provided with casters, and means for detachably connecting said units for mutual support with each

resting upon the floor, substantially as described.

In testimony whereof I affix my signature in the presence of two witnesses.

ALBIN HELLFRITZSCH.
